UNITED STATES PATENT OFFICE.

ARVID W. EKSTROM, OF LOS ANGELES, CALIFORNIA.

FURNACE.

1,044,763.

Specification of Letters Patent. Patented Nov. 19, 1912.

Application filed October 14, 1911. Serial No. 654,728.

To all whom it may concern:

Be it known that I, ARVID W. EKSTROM, a citizen of Sweden, residing at Los Angeles in the county of Los Angeles and 5 State of California, have invented new and useful Improvements in Furnaces, of which the following is a specification.

This invention relates to improvements in furnaces adapted for the carrying out of 10 chemical or metallurgical processes, and it is the principal object of the invention to provide an apparatus capable of reducing chemical compounds, ores or the like.

It is a further object of the invention to 15 provide a furnace in which materials may be treated by a reducing agent introduced into the furnace and gasified within the same.

It is also an object of the invention to 20 provide a furnace in which materials to be reduced may be inserted without previous mixing with a reducing agent, which materials may then be treated with a reducing agent also introduced in the furnace, with- 25 out the presence of air.

It is a further object of the invention to employ a furnace provided with one or 30 more retorts or muffles, and when more than one are used, they are adapted to successively receive materials to be treated, the said retorts being arranged so that a reducing agent may be introduced into one retort and converted into gaseous form and then led into another retort for further action upon 35 the charges of material to be reduced, portions of the gas being also employed externally of the retorts for producing combustion necessary to heat the same.

In the accompanying drawing forming a 40 part of this specification, Figure 1 is a longitudinal vertical sectional view through a furnace embodying the features of the present invention. Fig. 2 is a transverse sectional vertical view through the said furnace taken upon the line 2—2 of Fig. 1. Fig. 3 is an enlarged detail sectional view 45 through a portion of one of the side walls of the furnace showing the ducts and passages for delivering the gases generated in 50 the furnace to the combustion chamber.

While the furnace forming the subject matter of the present invention may be provided with any desired number of retorts, a furnace provided with two retorts prop-

erly connected is well adapted for accomplishing the purposes desired and for the proper illustration of the invention the drawing illustrates a double muffle apparatus, adapted for the use of oil as reducing agent.

3 and 4 indicate muffles or receptacles formed of earthen-ware or iron, according to circumstances; said muffles are mounted in a furnace structure 5, the walls thereof being made of any usual or suitable material. The muffles may be located upon transversely horizontal grids 6 and 7 mounted in the furnace 5, in such a manner that sufficient spaces around the said muffles be formed allowing the products of combustion to pass upwardly around and between said muffles and thence outwardly through any suitable outlet flue 8 or channel.

A space is left below the lower muffle to 75 form the combustion chamber 9, into which a burner 10 or other heating means is extended through an aperture 11 in the rear wall of the furnace. The muffles are formed open at the front end, the said end projecting through the front wall of the furnace 5 and being adapted to be tightly sealed by doors 12 and 13. When the muffles are to be closed the doors are put in place and are then tightly sealed. The door 12 of the 80 upper muffle is provided with a spraying nozzle 14 of any desired type for introducing oil or other fuel materials in sprayed form into said muffle. The said door 12 is also provided with an aperture 15 adapted 85 to be closed with a flap 16. The latter affords a means for introducing rakes or other implements into the muffle for distributing and moving the materials therein; it may also be used as a peep hole for observing the charge. The lower door 13 is like the upper one provided with an opening 17 and a flap 18 thus affording access 90 to the interior of the lower muffle 4.

The two muffles are connected by a vertical chute 19 which is made to extend almost the entire width of the muffles but may be narrower in cross section as shown in Fig. 1. The passage formed in said chute 19 is made with downwardly flaring walls 100 so that the materials passing through the same cannot become clogged therein. The upper muffle is charged by means of a hop-

per 20 mounted upon the top of the furnace and communicating with the said muffle by means of a connecting passage 21 formed in the top of the furnace and an aperture 22 in the wall of the muffle. A conical valve 23 adapted to fit in the outlet of the hopper and controlled by a hand lever 24 or similar device, may be employed to regulate the admission of materials to be treated in the furnace.

The chute 19 is located near the inner ends of the muffles so that materials treated in the upper muffle may be pushed into the passage in said chute and allowed to fall 15 into the lower muffle where they are again subjected to the hot gases evolved from the upper muffle. At a later period of the operation the lower muffle is discharged through a similar downwardly flaring chute 20 25 formed in the front wall of the furnace 5. The lower end of the said chute 25 communicates with a broad flat pipe or chute 26 so that the treated mass when finished may be led from the lower muffle to a receiving 25 vessel by operating a gate or other shut-off device. The side walls of the furnace are provided with horizontal gas ducts 28 as clearly shown in Figs. 1 and 2, the said ducts communicating with the chute 25 by means 30 of vertical passages 29. The ducts 28 communicate with the small chambers 33 by means of passages 30. From the chambers 33 horizontal slots 31 extend inwardly to the combustion chamber 9. There are preferably a 35 number of said slots extending along each side wall of the combustion chamber and the gases generated by treating the materials in the muffles will be conducted by the chute 25, the passages 29 and ducts 28 and passages 40 30 up to the chambers 33 and slots 31 where the gases escape into the combustion chamber 9 and become ignited for the purpose of heating the furnace. Sliding valves 32 are mounted in the small chambers 33 and 45 adapted to be regulated by a hook 34 or similar device. Small doors 35 serve for closing said chambers 33.

The materials after treatment in the second retort are discharged through the chute 26 into any suitable mechanism for further treatment in adapting the materials to other uses.

It will be further understood that the furnace may be provided with a larger number 55 of muffles than are shown in the drawing, the said muffles being preferably connected in series, usually so that the material treated may be allowed to drop from one muffle into the other as shown in the drawing, without 60 departing in the least from the spirit of the invention.

The materials to be reduced are placed in the hopper 20 and suitable charges thereof are introduced into the upper muffle 3 by

operating the valve 23. After closing said 65 valve 23 the materials are spread out in a layer upon the bottom of the muffle to a convenient thickness. The materials are reached through the opening 15 of the door 12 so that they may be handled by hoes, 70 hooks or similar implements. This operation being performed the temperature in the furnace is raised by means of the burner 10 to a sufficient degree to bring the materials to the temperature of reduction, whereupon 75 the air of the muffle system is expelled by means of any suitable steam-jet, not shown. In the form of a spray the oil is then introduced into the muffle from the nozzle 14, the oil being usually forced by pressure to form 80 a finely divided spray. When the oil thus sprayed comes in contact with the heated charge or the walls of the muffle, it will immediately be gasified and the gases will tend to reduce the charge and said gases will pass 85 down through the chute 19 to the lower muffle 7 where they will further reduce a preceding charge which has been delivered from the upper muffle.

The charge in the upper muffle is allowed 90 to remain until the same has reached the proper temperature or as long as experience teaches, whereupon it is caused to drop through the chute 19 to the lower muffle 4, where it is again spread into a suitable layer 95 by means of implements inserted through the door 17. A new charge is simultaneously being introduced into the upper muffle 3 as above described. In the lower muffle 4 the charge is allowed to remain until it is 100 as completely reduced as possible, whereupon it is discharged through the outlet chute 25 and pipe 26 to the receiving vessel. During all this time oil is allowed to flow continually for the purpose of generating 105 gas and when the flaps 16 and 18 are opened to stir or move the charges of the muffles, the gas within having a slight pressure due to its generation, has a tendency to shoot out of the apertures 15 and 17 thus preventing 110 the air entirely from entering the muffles and coming in contact with the materials therein which usually at the temperature of reduction will readily be oxidized.

It will be noted that in this furnace mechanism oxidation of the charge due to the presence of air is fully guarded against from the time the materials enter the reducing chamber until leaving the same.

The upper muffle 3 serves for the complete 120 gasification of the oil and also for heating of the gas formed therein, for the heating of a new charge, and partially for the reduction of the same. The lower muffle is adapted for the complete reduction of the 125 charge which was previously treated in the upper muffle. The lower muffle is arranged in the furnace described as closely to the

source of heat as suitable, so that the temperature of the same is somewhat higher than that of the upper muffle thus facilitating the final reduction. Occasionally the 5 charges are stirred by means of hooks in order to aid the reaction.

The construction of the furnace is such that when the temperature has been raised sufficiently high the oil burner 10 may be 10 gradually shut down, more oil being simultaneously introduced through the nozzle 14 into the upper muffle 3 producing an additional quantity of gas within the muffles. At a certain point the oil burner 10 may be 15 entirely shut off, the oil sprayed from the nozzle 14 supplying sufficient amount of gas for both the reduction of the charge and for the maintenance of the proper temperature of the furnace, the combustible gases from 20 the muffles being burned as they escape from the slots 31 in the combustion chamber 9.

In place of the oil spray delivered at the nozzle 14 as above described, an oil steam spray or producer gas, or natural gas or 25 pulverized coal or other reducing agents may be injected into the muffle system for producing a reducing agent and also for the external heating of the muffles.

The air required for the combustion of 30 the gas enters through the aperture 11 which preferably could be connected with a system of channels arranged in a way so that the hot waste gases from the furnace may be utilized for preheating the air of combustion, thus economizing the procedure.

It will be observed that a furnace constructed as above is adapted to carry out a process of ore treatment or the treatment of other chemical compounds in a continuous 40 manner, and that it possesses a great advantage in that the materials to be reduced may be placed in the reduction chamber or chambers without being previously mixed with the reducing agent. It affords a means for 45 treating certain materials with a reducing agent in a gaseous form which is productive of a more thorough and economical result. During the operation the air can not come 50 in contact with the very easy oxidizable charge.

It will further be seen that the gases evolved by the treatment of the materials in the reduction chamber or chambers are utilized for heating said chamber or chambers, the furnace being a gas producer as 55 well as a reduction apparatus.

What I claim is:

1. A reducing furnace provided with a plurality of reducing chambers having connecting passages, a nozzle extending into the upper reducing chamber whereby a liquid reducing agent may be injected into the same, means for heating the reducing chambers, the heat producing a gas of said

reducing agent, the lower reducing chamber 65 only having an outlet for gases whereby the reducing agent must pass through the upper and then the lower reducing chambers in succession to assist in reducing the materials with an increasing heat. 70

2. A reducing furnace comprising upper and lower reducing chambers, a connecting neck extending from one to the other and having a downwardly flaring passage formed therein permitting of the delivery of 75 materials treated from one reducing chamber to the other, the lower reducing chamber being also provided with a downwardly flaring discharge passage, the furnace being formed with a combustion chamber below 8 the said reducing chambers, means for injecting a reducing agent into the upper reducing chamber, the gases formed in said chamber being forced to pass downwardly into the lower chamber and thence outwardly through the discharge chute, and means for directing the gases into the combustion chamber whereby they will be burned for heating the reducing chambers. 85

3. A furnace comprising upper and lower 90 muffles closed against the inlet of air, a combustion chamber being arranged below said muffles, space being permitted for the products of combustion to pass upwardly therefrom around said muffles, means for introducing a liquid reducing agent into the upper muffle, means for introducing materials to be treated into said upper muffle, a downwardly flaring chute adapted to conduct the materials and the gases from the upper 100 muffle into the lower muffle, the lower muffle having a downwardly flaring discharge chute adjacent to the combustion chamber, the wall of the furnace being provided with flues connected with said chute whereby the 105 gases from the muffles are directed to the combustion chamber, the said furnace wall being provided with valve controlled outlets entering the said combustion chamber whereby the gases may be burned in the combustion chamber for heating the muffles, the structure being such that the materials to be treated and the gasified reducing agent will be increasingly hot toward the discharge chute, producing a more thorough 110 reduction of the materials and delivering the gases for combustion in a very hot condition. 115

4. A furnace having a combustion chamber formed within its walls, muffles extending into said combustion chamber and having a connecting chute leading from one to the other within said combustion chamber, whereby materials passing through the same will not be cooled, one of said muffles having a discharge chute formed in the walls of the furnace, the said furnace walls also having 120 passages leading from the sides of the

4
chute to the combustion chamber for delivering the gases resulting from the action in the muffles for burning, and a nozzle in the upper muffle adapted to direct a reducing agent into the same, the structure being such that the reducing agent must pass into the lower muffle before finding an outlet.

In witness that I claim the foregoing, I have hereunto subscribed my name this 9th day of Oct., 1911.

ARVID W. EKSTROM.
